ADZ FINISH ORNAMENTAL WOODWORKING MACHINE

Filed March 9, 1928

FIG. 5

FIG. 1

FIG. 2

FIG. 3

INVENTOR.
GEORGE P. DRISKELL

BY

A. B. Bowman
ATTORNEY

UNITED STATES PATENT OFFICE

GEORGE P. DRISKELL, OF SAN DIEGO, CALIFORNIA

ADZ-FINISH ORNAMENTAL WOODWORKING MACHINE

Application filed March 9, 1928. Serial No. 260,328.

My invention relates to a machine for providing an adz finish to wood surfaces and the objects of my invention are: first, to provide a machine for finishing wood surfaces so that they have the appearance of an adz finish; second, to provide a machine of this class which will reproduce the ordinary adz finish to wood surfaces in symmetrical or nonsymmetrical form as desired; third, to provide a machine of this class the cutting of which is done by an electrical power machine; fourth, to provide a machine of this class which is adjustable for different width beams or members to be adzed; fifth, to provide a machine of this class which may be operated while the operator is in seated or standing posture as desired; sixth, to provide a novel cutter for machines of this class, and seventh, to provide a machine of this class which is very simple and economical of construction, efficient, easy to operate and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a side elevational view of my machine shown positioned upon a piece of wood to be provided with an adzed finish on its upper surface; Fig. 2 is a top or plan view thereof; Fig. 3 is a transverse sectional view through 3—3 of Fig. 2 and showing by dotted lines an adjusted position of the guide members; Fig. 4 is an enlarged side elevational view of the cutting device, and Fig. 5 is a side elevational view at right angles thereto.

Similar characters of reference refer to similar parts and portions throughout the several views of the drawings.

The main side members 1 and 2, adjustable supports 3 and 4, roller 5, adjustable guides 6 and 7, weight 8, gage member 9, electrical drill motor 10, clamp member 11, motor sup-

porting plate 12, cutter 13 and handle members 14 constitute the principal parts and portions of my adz finishing machine.

The side members 1 and 2 are relatively broad and at their front ends are provided with slots 1^a and 2^a respectively in their outer side surfaces adapted to receive the supporting members 3 and 4 and these members are held in adjusted relation on the members 1 and 2 by means of thumb screws 1^b and 1^c, thus providing means for raising and lowering the frame composed of the members 1 and 2 and the cross bars. It will be noted that these members 1 and 2 are spaced apart by means of cross bars 15 and 16 and are positioned so that they are spaced relatively close together at their front ends and a greater distance apart at their rear ends. Revolubly mounted in the lower end of the supports 3 and 4 is a roller 5 which is adapted to rest upon the upper surface of the material to be finished. Positioned between the supports 3 and 4 is a cross bar 17 upon which is shiftably mounted a pair of adjustable guide members 6 and 7 which are provided with slots 6^a and 7^a in which are mounted wing screws 6^b and 7^b and it will be noted that these members overlap each other and are adapted to be clamped by means of the wing screws 6^b and 7^b for holding the members 6 and 7 in certain relative spaced relation to each other, thus providing adjustable guides for varying width members. Positioned on the inner surfaces of the guide members 6 and 7 at their lower ends are roller members 6^c and 7^c which are adapted to reduce the friction against the side surfaces of the timbers. Shiftably mounted in the outer surfaces of the members 1 and 2 positioned in grooves 1^d and 1^e is a U-shaped gage member 9, the lower side of which is adapted to rest on the timber to be finished when the desired depth of cut has been made. The upwardly extending portions of the members 9 are adjustably mounted in these grooves and clamped in position by means of screws 9^a having wing heads. Supported on the members 1 and 2 and positioned between the cross members 15 and 16 is a weight 8 preferably of cast

iron or cement which is adapted to provide sufficient weight on the machine to hold it down in proper position while operating. Positioned between the members 1 and 2, back of the member 16, is a plate 12 provided with a central hole therein and mounted on the upper surface around said hole is a clamp member 11 which is of the proper size to fit around the base portion of a conventional electric drill, as shown by 10, which is supported on the plate 12 and held securely by means of the clamp member 11. The driven portion of said drill extends downwardly and secured on the lower end thereof is a laterally offset relative to the axis of the drill cutter head 13 which is preferably metallic and provided with a slot 13^a therein in which is adapted to be mounted a cutter member 13^b. Slightly spaced from this cutter member 13^b in the member 13 is a slot 13^c which is provided with an enlarged portion into which is fitted a tapered pin 13^d and in the upper portion of the slot 13^a is a tapered rectangularly shaped key 13^e. It will be noted that the cutter member 13^b is of considerable length and is adapted to be positioned on an angle and substantially to one side of the drill axis, as shown best in Fig. 5 of the drawings, and may be positioned on varying angles and adjusted by means of the key 13^e and is held in position by means of the metal between the members 13^a and 13^c and adapted to be shifted by driving the metal pin 13^d into position, all as shown best in Figs. 4 and 5 of the drawings. It will be here noted that the particular shape of the cutter shown in Figs. 4 and 5 with the one end lower than the other provides when revolved a concave surface which when shifted simulates an adz cut. The rearwardly extending ends of the members 1 and 2 are provided with downwardly turned handle portions 1^f. Adjustably mounted on the sides of the members 1 and 2 just back of the cutter member is a handle consisting of the members 14 with cross members 14^a and 14^b. These members 14 are supported by means of wing screws the upper ones of which are mounted in slots in the members 14, thus providing for shifting the handle member consisting of the members 14 and 14^b to various angular positions relative to the members 1 and 2. It will be here noted that the handle members 1^f are to be used when the operator is positioned in a sitting posture while the others are to be used when in a standing posture.

The operation of the machine is as follows:

- 60 The machine is positioned on the timber, as shown best in Figs. 1, 2 and 3 of the drawings. The guide member 9 is adjusted to provide for cutting the proper depth adz finish in the upper surface of the timber.
- 65 The operator then starts the electric motor

10 and supports the rear end of the machine by either the handles 1^f or 14 and lets the cutter member down onto the upper surface of the wood in the varying positions desired. The gage 9 prevents the cutter from cutting 70 too deep and the operator shifts the cutter head to varying positions on the upper surface of the wood and moves it along on the roller 5. The cutter member 13^b thus provides finished adz surface to the upper surface of the timber. 75

Though I have shown and described a particular construction, combination and arrangement of parts and portions I do not wish to be limited to this particular construction, combination and arrangement but desire to include in the scope of my invention the construction, combination and arrangement substantially as set forth in the appended claims. 80

Having thus described my invention, what I claim as new and desire to secure by Letters Patent is:

1. In a machine of the class described, a frame member, an adjusting support having a base portion mounted on the front end only thereof, handles on the rear end thereof, a gage intermediate the front support and said handle, an electric motor mounted on said frame with a stock extending downwardly adjacent the said gage and a cutter mounted on the lower end of said stock said frame member being pivotable around the base of said support. 90

2. In a machine of the class described, a frame member, adjustable supports having a base portion mounted on the front end only thereof, a roller provided on the lower end of said supports, handles on the rear end of said frame, a gage positioned intermediate the front supports and said handles, an electric motor secured to the frame with its shaft extending downwardly and a cutter secured to the lower end of said shaft said frame member being pivotable around the base of 95 said support. 100

3. In a machine of the class described, a frame, a weight positioned on said frame, supports adjustably mounted on the front end only of said frame and extending downwardly, a roller positioned on the lower ends of said supports, a gage mounted on said frame and extending downwardly adapted to engage the surface of the timber to be finished at a predetermined depth of cut, an electric motor mounted on said frame with its shaft extending downwardly and a cutter mounted on the lower end of said shaft said frame member being pivotable around the axis of said roller. 115

4. In a machine of the class described, a frame, a weight positioned on said frame, supports adjustably mounted on the front end only of said frame and extending downwardly, a roller positioned on the lower ends 120

of said supports, a gage mounted on said frame and extending downwardly adapted to engage the surface of the timber to be finished at a predetermined depth of cut, an electric motor mounted on said frame with its shaft extending downwardly, a cutter mounted on the lower end of said shaft and a handle adjustably mounted on an angle to said frame and extending upwardly from the rear end thereof.

5. In a machine of the class described, a frame, a weight positioned on said frame, supports adjustably mounted on the front end of said frame and extending downwardly, a roller positioned on the lower ends of said supports, a gage mounted on said frame and extending downwardly adapted to engage the surface of the timber to be finished, an electric motor mounted on said frame with its shaft extending downwardly, a cutter mounted on the lower end of said shaft, a handle adjustably mounted on an angle to said frame and extending upwardly therefrom and guide means adjustably mounted 20 on said supports and extending laterally and downwardly therefrom.

6. In a machine of the class described, a frame, a weight positioned on said frame, supports adjustably mounted on the front end of said frame and extending downwardly, a roller positioned on the lower ends of said supports, a gage mounted on said frame and extending downwardly adapted to engage the surface of the timber to be finished, an 30 electric motor mounted on said frame with its shaft extending downwardly, a cutter mounted on the lower end of said shaft, a handle adjustably mounted on an angle to said frame and extending upwardly therefrom, guide means adjustably mounted on said supports and extending laterally and downwardly therefrom and rollers mounted on the inner sides of said guide members.

7. In a device of the class described, a shank, a head at the end of said shank provided with an angular slot open at its lower end, said slot extending substantially at right angles to said shank, a tapering cutter member mounted therein with a thin edge at its 50 lower side extending below said head and set on an angle with one end lower than the other, another slot spaced slightly therefrom in said head parallel therewith and a wedge mounted in said slot.

55. 8. In a device of the class described, a shank, a head at the end of said shank provided with an angular slot open at its lower end, said slot extending substantially at right angles to said shank, a tapering cutter member mounted therein with a thin edge at its lower side extending below said head and set on an angle with one end lower than the other, another slot spaced slightly therefrom in said head parallel therewith, a wedge 60 mounted in said slot and a wedge mounted

in the upper edge of said slot above said cutter member.

9. In an adz ornamental finish woodworking machine, a frame member, an adjustable support having a base portion mounted on the front end only thereof, upon which said frame is pivotally and shiftably mounted, handles on the rear end thereof, a gage intermediate the front support and said handles for limiting the downward movement of said frame at the rear and an electric motor mounted on said frame with a stock extending downwardly adjacent said gage and a cutter with a beveled cutting surface mounted on the lower end of said stock for producing concave cut 70 surfaces.

10. In a machine for simulating adz finish, a frame member, roller means at the front end only thereof around the axis of which said frame is pivotally mounted so that the rear end may be raised and lowered and shifted sidewise, handles on the rear end thereof, a gage positioned intermediate the front supports and said handles and extending downwardly for gaging the downward movement of the rear end thereof, and electric motor mounted on said frame adjacent said gage with a stock extending downwardly and a cutter mounted on the lower end of said stock.

95 11. In a machine for simulating adz finish, a frame member, roller means at the front end only thereof around the axis of which said frame is pivotally mounted so that the rear end may be raised and lowered and shifted sidewise, handles on the rear end thereof, a gage positioned intermediate the front supports and said handles and extending downwardly for gaging the downward movement of the rear end thereof, an electric 100 motor mounted on said frame adjacent said gage with a stock extending downwardly and a cutter with a beveled cutting surface mounted on the lower end of said stock for producing concave adz simulating surfaces.

110 In testimony whereof, I have hereunto set my hand at San Diego, California, this 2nd day of March, 1928.

GEORGE P. DRISKELL.
